UNITED STATES PATENT OFFICE.

ISAAC APPELMAN, OF BROOKLYN, NEW YORK, ASSIGNOR TO PREMIER SPECIALTY CO., OF BROOKLYN, NEW YORK, A CORPORATION OF NEW YORK.

WIND-PROPELLED TOY.

Application filed July 15, 1925. Serial No. 43,729.

This invention relates to a wind propelled toy and relates more particularly to an improved wind wheel toy in which the wind propelled devices operate other members, such as toy figures or the like.

The principal objects of my present invention comprehend the provision of a wind wheel toy of the character in which the wind propelled wheels are co-related with other members such as toy figures for setting the latter into operation when the wind wheel is rotated, the improvements consisting in the provision of means associating the wind propelled devices with the operable figure so that the said figure may be operated in a positive manner without interfering with or hindering the rotation or operation of the wind propelled wheel, in the further provision of means whereby the operated member or figure may be positioned into or out of co-action with the wind propelled wheel at the will of the user so that the wind wheel may be operated separately and independent of the toy figure, and the still further provision of an improved wind wheel or pin wheel in which the aforesaid parts are associated in a simple way with a minimum of operative connections therebetween, whereby a toy having a simple law of operation is provided which may be manufactured with uniformity by quantity production methods at a very low cost.

To the accomplishment of the foregoing and such other objects as may hereinafter appear, the invention consists in the elements and their relation one to the other, as hereinafter particularly described and sought to be defined in the claims; reference being had to the accompanying drawing which shows the preferred embodiment of my invention, and in which:

Fig. 1 is a perspective view of the improved wind wheel toy of my invention, and Fig. 2 is a side elevation thereof.

Referring now more in detail to the drawings, the wind wheel toy of the present invention comprises wind propelled devices generally designated as A arranged for co-action with an operated member such as a toy figure B for imparting movement to the latter when the wind propelled devices rotate, the said wind propelled devices and toy figure being mounted for movement on a support generally designated as C.

The support C comprises an elongated 55 supporting member such as 10 preferably made of wood, and a member 11 bent to U-shaped form and including the transverse or horizontal sections or arms 12 and 13 fixed at spaced points to the support 10 and the 60 connecting vertically arranged section 14, the arm section 12 defining a shaft for the wind propelled devices A and the connecting section 14 defining a shaft for the operable toy figure B.

The wind propelled devices A comprise one or more wind wheels 15 and 16, each preferably made of a single blank of sheet material such as celluloid, each of said wheels being preferably bi-bladed as clearly shown in the drawings. The said bi-bladed wheels 15 and 16 are mounted for free rotation on the shaft 12 and are separated from each other and from the elongated support 10 by means of the spacing sleeves 17 and 18, the said blades being held against axial motion by means of a friction washer 19 which preferably comprises a rubber ring frictionally held on the shaft 12. The friction washer 19 may be axially adjusted to give any desired pressure to tighten or loosen the blades to meet the needs or desires of service.

As heretofore mentioned, one of the prime objects of the present invention comprehends the provision of an improved wind propelled toy in which the toy figure B is so related to the wind wheel that the former is operated in a positive manner without hindering or interfering with the revolution 90 of the wind wheel, the parts being further so correlated as to permit the movement of the toy figure into and out of co-action with the wind wheel. These and other objects of the invention are accomplished by the 95 provision of the operable member B comprising a toy figure 20 preferably made of sheet material, the said toy figure being mounted on the shaft portion 14 for rotation by means of upper and lower angle 100 pieces 21 and 22 fixed to spaced portions of the body of the toy figure and apertured to receive the shaft portion 14, the said figure being positioned on the shaft for rotation thereabout by means of a friction member 105 23. The friction member 23 preferably consists of a rubber washer or ring which may be slid or moved along the shaft portion 14

to adjustably position the figure on the shaft for purposes described more fully hereinafter.

To accomplish the results desired, the figure 20 is provided with a means which may be positioned in the path of revolution of one of the wind wheels, such for example as the wind wheel 16, and which is adapted to be struck by the latter in its revolution for revolving the toy figure in unison therewith. In the preferred construction such means comprises a star wheel 24 affixed to the head of the figure 20 and preferably to the upper angle piece 21, such star wheel being free from connection with the wind wheel 16 as clearly shown in Figs. 1 and 2 of the drawings and lying in a plane normal to the plane of revolution of the wind wheel so that the points of the star wheel may be engaged intermittently by the blades of the pin wheel 16 during rotation of the latter. The star wheel 24 and the pin wheel 16 thus cooperate in the nature of an intermittently operating mechanism, the parts of which are unconnected to each other so that both may be free to rotate and may be free to interengage during operation.

By the provision of this cooperation between the parts, it is found that both the wind wheel and the toy figure are positively rotated without the interference which usually results from the provision of connecting members between the parts. Moreover, by positioning the star wheel so as to be directly engaged by the blades of the wind wheel the full force of the latter is imparted to the star wheel to set the toy figure into rapid revolution. It will be also noted that by making the toy figure of sheet material not only is a light-weight construction produced but the body of the figure during rotation does not collide with the rotating wind wheel, leaving the same free to cooperate mainly with the star wheel 24.

It has been found desirable to provide means for adjustably relating the toy figure with the wind propelled wheel so as to position the star wheel relatively to the blades of the wind wheel to produce an operation to suit the desires or taste of the user, and also to position the toy figure out of coaction with the wind wheel to permit the latter to be used separately and apart from the toy figure. To these ends the friction ring or washer 23 is provided and the shaft is made long enough so as to permit the longitudinal adjustment of the figure 20 on the shaft. When it is desired to position the figure out of co-action with the wind propelled wheel the ring 23 is moved to its bottommost position with the legs 25 and 26 of the figure 20 straddling the horizontal portion 13 of the support 11. When so positioned the wind wheels are free to move without engaging the star wheel 24. If de-

sired the legs 25 and 26 may be pivotally connected as at 27 and 28 respectively to the body of the figure 20 so that during rotation of the figure the legs will fly out by centrifugal action.

The operation and use of my improved wind operated toy will in the main be fully apparent from the above detailed description thereof. It will be further apparent that the parts of the wind propelled toy are correlated so as to permit the manufacture and assembly of the same in quantity with rapidity and facility at a low cost, producing an inexpensive toy which may be adjusted by the child to suit individual requirements, the parts of which may be moved to positions to give a variety of attractive operations. It will be apparent also that while I have shown the invention in the preferred form that many changes may be made in the construction and arrangement of the parts thereof without departing from the spirit of the invention defined in the following claims.

I claim—

1. A wind wheel toy comprising a support including a shaft, a wind propelled wheel mounted to revolve on said shaft, a second shaft arranged at an angle to said first shaft, a toy figure mounted to revolve on said second shaft and means attached to said toy figure and lying in the path of revolution of said wind wheel adapted to be intermittently struck by the latter in its revolution for revolving the toy figure.

2. A wind wheel toy comprising a support including a shaft, a wind propelled wheel mounted to revolve on said shaft, a second shaft arranged at an angle to said first shaft, a toy figure mounted to revolve on said second shaft and adjustable to and from the wind propelled wheel, means attached to said toy figure and lying in the path of revolution of said wind wheel adapted to be struck by the latter in its revolution for revolving the toy figure and means for positioning the toy figure into or out of coaction with the wind propelled wheel at the will of the operator.

3. A wind wheel toy comprising a support including a shaft, a wind propelled wheel mounted to revolve on said shaft, a second shaft arranged at an angle to said first shaft, a toy figure made of sheet material mounted to revolve on said second shaft and means attached to said toy figure and lying in the path of revolution of said wind wheel adapted to be intermittently struck by the blades of the wind wheel in its revolution for revolving the toy figure.

4. A wind wheel toy comprising a support including a shaft, a wind propelled wheel mounted to revolve on said shaft, a second shaft arranged at an angle to said first shaft, a toy figure mounted to revolve

on said second shaft and a star wheel attached to said toy figure and lying in a plane normal to the plane of revolution of said wind wheel adapted to be intermittently struck by the latter in its revolution for revolving the toy figure.

5. A wind wheel toy comprising a support including a shaft, a wind propelled bi-bladed wheel mounted to revolve on said shaft, a second shaft arranged at right angles to said first shaft, a toy figure made of sheet material mounted to revolve on said second shaft, a star wheel attached to said toy figure and lying in a plane normal to the plane of revolution of said wind wheel adapted to be intermittently struck by the latter in its revolution for revolving the toy figure, and means for adjusting the position of said figure toy longitudinally on its shaft.

6. A wind wheel toy comprising an elongated support, a member bent to U-shaped

form, fixed to said support, one section of said member defining a shaft, a wind propelled bi-bladed wheel mounted to revolve 25 on said shaft, another section of said member defining a second shaft arranged at right angles to said first shaft, a toy figure made of sheet material mounted to revolve about said second shaft, a star wheel also 30 made of sheet material attached to said toy figure and lying in the path of revolution of said wind wheel adapted to be intermittently struck by the latter in its revolution for revolving the toy figure, and a friction 35 ring on said second shaft movable for adjustably predetermining the position of said toy figure and star wheel relative to the wind propelled wheel.

Signed at Brooklyn in the county of 40
Queens and State of New York this 1st day
of July A. D. 1925.

ISAAC APPELMAN.
